Application January 10, 1952, Serial No. 265,787

Claims priority, application Great Britain
January 15, 1951

4 Claims. (Cl. 261—28)

This invention relates to a pump device for producing foam and more particularly to such a device of the kind which has a gauze-pack and a rotary vane type pump arranged to force foam forming mixture issuing from the pump outlet through the gauze-pack.

Broadly, in accordance with the invention, there is provided a pump device of the kind referred to, wherein the inlet to the pump communicates with a tank intended to have a mixture of water and foam stabiliser fed thereto, said tank being open to the atmosphere, and the arrangement being such that when the pump is in operation the latter draws mixture from the tank and draws air through the tank, the foam produced then issuing from the gauze-pack.

For a better understanding of the invention, and to show how the same may be carried into effect, reference will now be made to the accompanying drawings, in which:

Figure 1 is a cross-sectional elevation of a pump device, and

Figure 2 is a view on II—II of Figure 1.

The pump device shown in Figures 1 and 2 has a cylindrical chamber 1 in which a cylindrical rotor 2 is mounted. The rotor extends the length of the chamber (Figure 2) and the longitudinal axes of the chamber and the rotor are parallel, but not coincident (Figure 1). The axis of the rotor 2 is so disposed in relation to the axis of the chamber 1 that a portion 1A of the inner wall of the chamber almost contacts the periphery 2A of the rotor 2. The rotor and inner wall of the chamber, where they are almost in contact, are close enough to provide a seal 3 extending the length of the rotor. Around the rest of the periphery 2A of the rotor there is a gap between the rotor and the inner wall of the chamber, the gap being largest opposite the location of the seal 3.

The rotor 2 has five radially directed deep grooves 4 (Figure 1) cut along generators of the curved surface thereof. The grooves 4 extend the length of the rotor 2. A vane 5 consisting of a plate is slidably located in each groove 4.

The rotor 2 is in the form of five hollow segments 6 open at each end and each having a centrally positioned web 7 for strengthening purposes. Each web 7 has a hole 8 therethrough.

An inlet 9 (Figure 2) in the form of a slot extending the length of the chamber 1 is cut in the wall of the latter. The inlet 9 commences at 10 (Figure 1) slightly more than one vane pitch from the seal 3 and terminates at 11 one vane pitch after its commencement. The termination 11 is located at the bottom of a pump device.

A tank 12 open at the top 13 to the atmosphere communicates with the inlet 9. The top 13 of the tank 12 is above the commencement 10 of the inlet 9 and the bottom 14 of the tank 12 is level with the bottom of the chamber. The tank 12 extends throughout the length of the inlet 9 and that side of the tank that is adjacent the inlet 9 is entirely cut away so that the tank 12 freely communicates with the inlet 9. An inlet conduit (not

shown) from a constant head device (also not shown) leads into the top 13 of the tank 12. The tank 12 contains a curved guide plate 15 (Figure 1) which extends from one end of the tank to the other. The upper end 15A of the plate 15 is secured to that side of the tank that is remote from the inlet 9. The lower end 15B of the plate 15 is supported on feet 16 at the bottom of the tank 12 and adjacent the inlet 9. A hole 17 is formed in the bottom of the tank, underneath the plate 15.

The outlet 18 from the chamber 1 commences at the seal 3 and extends over almost two vane pitches from the seal 3 in a direction opposite to the direction in which the commencement 10 of the inlet 9 was measured from the seal 3. The outlet 18 communicates with a short upwardly extending conduit 19 which is flanged at its upper end for enabling a flexible pipe to be attached thereto. A plurality of gauzes forming a gauze-pack 20 is secured across the conduit 19, the gauzes being placed one on top of the other and each gauze covering the bore of the conduit 19. The gauzes are separated from each other by rings acting as distance pieces.

A curved bar 22 extends across the inlet 9 and a further curved bar 23 extends across the outlet 18 of the pump device. These curved bars 22, 23 follow the curvature of the inner wall of the chamber 1 and serve to guide the vanes 5 whilst the latter are proceeding across the inlet 9 and outlet 18.

The pump device described above operates in the following manner.

The rotor 2 is rotated in the direction of the arrow 24, so that the outer edges of the vanes 5 proceed from the seal 3 to the inlet 9 and thence to the outlet 18. Water containing a foam stabilizer is fed to the constant head device and from thence to the tank 12. As the rotor 2 turns, the vanes 5 move outwardly under centrifugal action until their outer extremities encounter the inner wall of the chamber 1 and the bars 22, 23. A mixture of water, foam stabilizer and air is drawn through the inlet 9 and is carried around the chamber 1 to the outlet 18 through which it is expelled. The mixture is then forced through the gauze-pack 20.

It is to be understood that the rate of flow of water and foam stabilizer to the pump device is dependent solely upon the constant head device and is irrespective of the speed of rotation of the rotor 2. Since the top 13 of the tank 12 is open to atmosphere, an increase in the speed of the rotor 2 will increase the amount of air drawn through the pump device but will not materially increase the amount of water and foam stabilizer forced through the pump device. The increase in the speed of the rotor, therefore, has the effect of increasing the proportion of air to liquid in the resultant foam. During operation of the pump device, considerable turbulence and mixing of the air and liquid in the tank 12 takes place on account of the rush of air into the tank 12.

The hole 17 remains open during operation of the pump device, the masking of the hole 17 by the plate 15 and the suction on the mixture flowing through the tank 12 preventing loss of mixture through this hole. When the rotor 2 is stopped, all liquid in the pump device drains through the hole 17.

In a modified form of the pump device described above shutters (not shown), for example, of the iris type, may be provided in the conduit 19 immediately before (that is to say, on the pump side of), the lowest and the uppermost gauze. These iris shutters would operate in a similar manner to those used in optical apparatus for varying the sizes of apertures. In the present application the two shutters would serve to vary the effective cross-sectional area of the gauze-pack 20.

For the production of good foam it is necessary that the mixture flowing from the outlet 18 of the chamber

1 should flow full bore through the gauze-pack 20. When the rotor 2 is rotating at relatively low speeds, however, the mixture flowing from the outlet 18 may not flow full bore through the conduit 19. The iris shutters would, therefore, be adjusted to reduce the effective cross-sectional area of the gauze-pack 20 to such an extent that the mixture would flow full bore through the cross-sectional area of the gauze-pack 20 that remained uncovered by the shutters.

The meshes of the individual gauzes in the gauze-pack 20 may differ. For example, the lower and upper gauzes may be of wide mesh, whereas the intermediate gauzes may be of fine mesh.

The grooves 4 which support the vanes 5 are not necessarily radially directed. They may be arranged tangentially to an imaginary circle concentric with the periphery of the rotor and of smaller diameter than that of the rotor. By so arranging these grooves, they can be cut deeper than when they are radially directed. By using deep grooves, it will be understood that the vanes can be more effectively supported than when shallow grooves are used. When the deeper grooves are used, it is preferable to provide some form of guide means for maintaining the outer extremities of the vanes against the wall of the chamber. Such guide means may, for example, take the form of a circular rib at one end of the chamber, the rib being concentric with the cylindrical chamber and engaging in slots cut in the ends of the vanes.

Deflectors (not shown) may be provided within the conduit 19, on the pump side of the gauze-pack 20, for spreading the mixture, emerging from the outlet 18, over the cross-sectional area of the gauze-pack 20.

The bars 22 and 23 as shown in the drawings are disposed vertically, but it is to be understood that it may be advantageous to position them diagonally across the inlet and outlet respectively.

We claim:

1. Pump means for producing foam from a mixture of water and foam stabilizer delivered to said pump means by a constant head device of known construction, comprising a hollow cylindrical chamber mounted with its longitudinal axis substantially horizontal, a rotor of substantially the same axial length as said chamber and supported eccentrically therein, a plurality of vanes ex-

tending along the length of said rotor, said vanes being respectively located in longitudinally directed slots opening through the rotor periphery, an outlet for the pumped mixture at the top of said chamber, a conduit communicating with said outlet, a gauze pack in said conduit, an inlet extending over the length of the chamber and from the bottom of the latter upwardly for at least one vane pitch, a tank having a large opening in one side thereof registering with said chamber inlet to provide direct unrestricted communication between said tank and chamber, inlet means at the top of said tank adapted to receive the delivery at a constant rate from said constant head device and also to provide a free unrestricted air inlet and a plate in said tank which inclines downwardly towards the bottom of said tank opening and is adapted to mask an open drainage hole for the pump means in the bottom of said tank.

2. Pump means according to claim 1 in which said gauze pack is close to said chamber outlet to ensure that mixed water, air and stabilizer forced through the outlet by the vane impinges directly at full bore on the gauze pack.

3. Pump means as claimed in claim 1 in which sectors of the said rotor formed between adjacent slots are hollow and are open at each end thereof.

4. Pump means as claimed in claim 1 in which the eccentric mounting of said rotor provides a line seal between the rotor periphery and chamber wall, which seal extends over the whole axial length of the rotor and is located immediately following said chamber outlet in the operative direction of rotation of said rotor.
